UNITED STATES PATENT OFFICE.

PHILIP JAMES KENT, OF DETROIT, MICHIGAN, ASSIGNOR TO MAXWELL MOTOR CORPORATION, OF HIGHLAND PARK, MICHIGAN, A CORPORATION OF WEST VIRGINIA.

DESIGN FOR AN AUTOMOBILE HEADLAMP.

Application filed April 13, 1925. Serial No. 13,098. Term of patent 14 years.

To all whom it may concern:

Be it known that I, PHILIP JAMES KENT, a citizen of the United States, residing at the city of Detroit, in the county of Wayne and State of Michigan, have invented a new, original, and ornamental Design for Automobile Headlamps, of which the following is a specification, reference being had to the accompanying drawing, forming a part thereof, in which—

Fig. 1 is a front elevation showing my design.

Fig. 2 is a side elevation showing my design.

What I claim is:

The ornamental design for an automobile headlamp, as shown.

PHILIP JAMES KENT.
